(57) CLAIM

The ornamental design for a skin massage device, as shown and described.

DESCRIPTION

FIG. 1 is a front perspective view showing the new, original, and ornamental design of a skin massage device; FIG. 2 is a front elevation view thereof;

FIG. 3 is a rear elevation view thereof;

FIG. 4 is a left elevation view thereof;

FIG. 5 is a right elevation view thereof;

FIG. 6. is a top plan view thereof; and,

FIG. 7 is a bottom plan view thereof.

The broken lines shown in the figures are for the purpose of illustrating portions of the skin massage device, which form no part of the claimed design.
